J. MAGINA

HARNESS OPERATED STOP MOTION DEVICE FOR LOOMS

Filed May 31, 1927

FIG. -2

INVENTOR
JOAO MAGINA
BY *Manuel C. Rosa*
ATTORNEY

UNITED STATES PATENT OFFICE.

JOAO MAGINA, OF NEW BEDFORD, MASSACHUSETTS.

HARNESS-OPERATED STOP-MOTION DEVICE FOR LOOMS.

Application filed May 31, 1927. Serial No. 195,411.

This invention has reference to a means for stopping the loom whenever the connections for the harness frames become broken or unduly slack.

5 To form a perfect shed, the harness straps must be held taut in order to raise and lower the harness members in a substantially horizontal plane. Should the harness straps become slack at any point the result would 10 be a harness member raised higher on one edge than on the other, permitting the warp threads at the low side to remain in the path of the shuttle which carries the weft threads through the open warp shed, resulting in 15 broken warp threads or ends referred to in the trade as "smashes".

Slackness of the harness straps will also cause loose woven fabric and fabric having some of the warp threads floating on the 20 under side of the fabric due to the fact that they were not raised to a proper level to be woven into the fabric. This condition may exist for a considerable length of time and the weaver would not be aware of the fact.

25 The principal object of my invention is to prevent such conditions by automatically stopping the loom immediately upon any one of the harness members becoming slack, which may be caused by a broken or strained 30 supporting strap or wire or any one of a number of different causes well known in the art of weaving.

Other objects and advantages will appear from the detailed description which follows.

35 I attain these objects and advantages by means of the mechanism described in the accompanying drawings wherein:

Figure 1 is a rear elevational view showing sufficient loom structure to illustrate the 40 mode of attachment of the harness operated stop motion.

Figure 2 is a cross sectional view through the loom showing the harness operated stop motion in clearer view.

45 Referring to the drawing, only sufficient loom structure is shown to illustrate the application of the device. The harness members 1 are shown suspended by straps 2 from a series of sheaves 3 there being an 50 individual sheave for each harness member. The sheaves are loosely mounted on a shaft 4 held with the loom arches 5. Disposed in front of the harnesses is the lay 6, the reel 7, the hand rail 8 and the lay sword 9 which is 55 pivotally mounted at its lower end (not shown). The warp threads 10 pass through

the eyelets in the harnesses and form the shed by being carried up and down in the usual way.

In Figure 2, my attachment is shown as 60 comprising suspension rods 11, 12, of which there is a pair on each side of the loom, which are secured by their hooked ends to the front and rear arches 5 of the loom through the openings 13 in the loom arches 65

5. A lever 14 having a sufficient curvature to clear the hand rail 8 is pivotally secured to the lower extremity of the front rod 11 and extends longitudinally of the loom as far back as the warp stop motion. The rear suspension rod 12 is located adjacent the innermost harness member. A sensitive helical spring 15 is secured to the lower extremity of the rod 12 by a collar 16, and set 70 screw. At the lower end of the spring there is provided an eye member 17 through which the lever rod 14 passes.

75 At the free end of the lever rod a drop device is attached. As shown in the drawings it consists of a flat strip 18 having a head portion 19 at right angles thereto for attachment on the lever rod. The flat strip has a tapered slot 20 therein for enclosing the normally moving part 21 of the warp stop motion device. The warp stop motion is not shown in detail as its mode of operation is familiar to anyone skilled in the art. The element 21 oscillates as on the Crompton and Knowles warp stop motion and the lower portion of the tapered slot of the drop 80 member above referred to is of sufficient size to allow the free normal movement of the element 21, whereas the narrow portion of the slot is of such width as to hug the oscillating element and restrain its movement.

85 The mode of operation is as follows: In the event that a harness becomes broken or unduly slack the impact of the harness on the lever rod causes it to fall and this descent is cushioned by the spring. The drop device slides down on the moving part of the warp stop motion and as the narrow end of the tapered slot is approached the moving part is held against movement whereby the loom is brought to a stop. The position of the drop means when lowered is shown by the dotted lines in Figure 2.

100 Although the drop device shown depends upon a tapered slot for its effect it should be understood that the drop device may be made serviceable with any type of stop motion by 105 simply suspending the drop device over the

moving part and its drop on the moving or rocking part will stop the loom. The drop device may be used suspended over the stop motion control as would be the case with the old types of stop motions when the tapered slot would be of no value. With the modern type of stop motion where the wires or rods have a square cross section the function of a tapered slot enclosing one of the wires or rods has been pointed out above.

All that has been said above in the description of my preferred embodiment is offered by way of illustration and not limitation. I do not wish to be limited to the exact structure of the preferred embodiment shown and described, or to any particular material used in the construction of parts, or to the design of parts, but desire protection as against any variations in structure which utilize the principle of my invention and fall within the purview of my invention and are within the spirit and scope of the following claims.

The invention having been set forth, what is claimed as new and useful is:

- 25 1. A harness operated stop motion for use in combination with the warp stop motion of a loom, comprising means suspended from said loom and disposed transversely within the harness members, a drop member attached to said means and being adapted when lowered to coat with a normally moving part of the warp stop motion to automatically stop the loom, said drop member being substantially O-shaped and having a tapered slot therein, said tapered slot being adapted to freely inclose the normally moving part of the warp stop motion during the normal operation of a loom.
- 30 2. A harness operated stop motion for use in combination with the warp stop motion of a loom, comprising means suspended from said loom and disposed transversely of the harness members, a drop means attached to said first mentioned means, said drop means having a tapered slot therein to freely ac-

commodate the normally moving part of the warp stop motion at its wider end, its narrow end being adapted upon the breaking of a harness of hugging said normally moving part to stop the loom.

5 3. In a loom, harness members, a warp stop motion, frontal and rear suspension rods hooked to the arches of the loom on each side thereof, forwardly and rearwardly of the harness members, a lever rod curved upwardly at one end is pivotally secured to the extremities of the frontal suspension rods, a sensitive resilient means attached to the extremities of the rear suspension rods, said lever rod being secured to the lower end of said resilient means whereby it is resiliently suspended, a substantially O-shaped drop means having a tapered slot therein secured to said lever rod at a point adjacent its free end, said O-shaped drop means being adapted in raised position to freely enclose the normally moving part of the warp stop motion and in lowered position to prevent its movement.

15 4. In a loom, the combination with the harnesses, and a warp stop motion to automatically stop the loom upon the breakage of a warp thread, of means passing through said harnesses, said means being suspended from said loom and being adapted to coat with a normally moving part of said warp stop motion to automatically stop the loom upon the falling of a harness upon a portion of said means, said means comprising frontal and rear suspension rods, a lever rod pivotally connected to said frontal rods, said lever rod being resiliently connected to said rear suspension rods, and drop means at the extremity of said lever rod for engaging the warp stop motion upon the depression of the lever rod.

20 Signed at Fall River, in the county of Bristol, State of Massachusetts, this twenty-first day of May, 1927.

JOAO MAGINA.
